DECORATIVE HOLDER

Antonio Puente, Caracas, Venezuela, assignor of a fractional part interest to Theodore Bernstein and Irving Schwartz, both of Elkins Park, Pa.

Filed July 18, 1972, Ser. No. 272,997

Term of patent 14 years

Int. Cl. D6—04

U.S. Cl. D6—186

FIG. 1

FIG. 4

FIG. 5

FIG. 2

FIG. 3

FIG. 6

FIG. 1 is a perspective view of the decorative holder showing my new design;

FIG. 2 is an end view thereof;

FIG. 3 is a side elevation view thereof;

FIG. 4 is a top plan view thereof;

FIG. 5 is a bottom plan view thereof; and

FIG. 6 is a sectional view taken along the line 6—6 in FIG. 1.

The other end view is identical to that shown in FIG. 2. The other side elevation view is identical to that shown in FIG. 3.

I claim:

The ornamental design for a decorative holder, substantially as shown and described.
